HAND WHEEL WRENCH

Wayne K. Bergman, Toledo, Ohio

Application October 26, 1953, Serial No. 27,337

Term of patent 14 years

(Cl. D54—16)

Fig. 1

Fig. 2

Fig. 3

Fig. 4

To all whom it may concern:

Be it known that I, Wayne K. Bergman, a citizen of the United States, residing at 947 Butler Avenue, in the city of Toledo, county of Lucas, State of Ohio, have invented a new, original, and ornamental Design for a Hand Wheel Wrench, of which the following is a specification, reference being had to the accompanying drawings, forming a part thereof.

Figure 1 is a perspective view of a hand wheel wrench showing my new design;

Figure 2 is a side elevation view thereof;

Figure 3 is a top plan view; and

Figure 4 is a second perspective view thereof.

I claim:

The ornamental design for a hand wheel wrench, as shown.
